Fig. I

Fig. II

Fig. III

Fig. 1 is a top plan view of a tape case, showing my new design;

Fig. 2 is a side elevational view thereof; and

Fig. 3 is a bottom plan view thereof.

The characteristic features of the tape case shown reside in the configuration and appearance of the central handle and front and rear escutcheon plates, most of the remainder of the case being covered with leather-like covering material.

I claim:

The ornamental design for a tape case, as shown and described,
